UNITED STATES PATENT OFFICE.

JOSEPH F. STACHOWSKI, OF APPLETON, WISCONSIN.

EXPANSION SHAFT.

Application filed March 16, 1927. Serial No. 175,806.

This invention relates to improvements in expansion shafts.

Heretofore, when material such as paper was to be rolled onto a core, the core was wedged onto the shaft to be revolved and when the roll was completed it was necessary to force it and the core from the shaft, force applied by means of a hammer being usually necessary with the result that the roll 10 was often damaged rendering unfit for use some of the paper thereon.

It is, therefore, the primary object of the present invention to provide an expansion shaft suitable for the above-mentioned uses 15 constructed so that a roll or core may be easily inserted thereon or removed therefrom without the use of a tool and without any damage to the roll.

A further object of the invention is to 20 provide a manually adjustable expansion shaft which will releasably and tightly engage a core or roll inserted thereon.

A further object of the invention is to 25 provide an expansion shaft in which the circumference of the clamping or engaging portion may be readily varied to suit the work.

A further object of the invention is to 30 provide an expansion shaft which is of very simple construction, is easily operated and adjusted, is inexpensive to manufacture, is strong and durable, and is well adapted for the purpose described.

A further object of the invention is to 35 provide an expansion shaft with which any machine for rolling material may be equipped.

With the above and other objects in view 40 the invention consists of the improved expansion shaft and its parts and combinations as set forth in the claims and all equivalents thereof.

In the accompanying drawing in which 45 the same reference characters indicate the same parts in all of the views:

Fig. 1 is a side view of the improved expansion shaft;

Fig. 2 is a longitudinal sectional view thereof;

Fig. 3 is a cross-sectional view taken on 50 line 3—3 of Fig. 2; and

Fig. 4 is a cross-sectional view taken on line 4—4 of Fig. 2.

Referring now more particularly to the drawing it will appear that the numeral

6 indicates an elongated shaft adapted to 55 be revolved by a machine of which it forms a part and the inner end portion of said shaft is built up by means of a collar 7 to a correct diameter to fit the machine bearing. An externally threaded cylindrical member 8 is shrunk onto the shaft 6 outwardly 60 of the collar 7 and between the inner end of said threaded member and the collar 7 another collar 9 is held tightly on the shaft 65 to protect the end portion of the threaded member.

An adjusting member 10 formed with a bore, the major portion of which is of a diameter considerably larger than that of the threaded member 8 and shaft 6, surrounds 70 said members and its bore at its inner end portion is reduced and threaded, as at 11, whereby said adjusting member has a screw engagement with the threaded member 8. The outer end portion of the adjusting member 75 is secured by means of screws 12, the ends of which ride in a groove 12' to a cylindrical portion 13 of a cone member 14 which is longitudinally movably mounted on the shaft 6. The outer end portion of the 80 cone member is tapered and polygonal in shape with flattened faces 15.

The intermediate portion of the shaft 6 has movably mounted thereon an elongated sleeve 16 and the inner end portion of said 85 sleeve enters an annular recess formed therefor in the end portion of the cone member 14 and abuts against a shoulder 17.

An outer cone member 18 is mounted on an outer portion of the shaft 6 and said cone 90 member is formed with an inner annular recess 19 into which the outer end portion of the sleeve 16 extends and engages the shoulder 20.

A stationary cone member 21 is also mounted 95 on the sleeve 16 between the cones 14 and 18 and suitably spaced from the cone 14, and said cone member 21 is secured to the shaft 6 by means of pins 22. The inner end portion of said cone member is tapered toward 100 the tapered end portion of the cone member 14 and is formed with similar flattened faces 23. The cone members 18 and 21 are connected by means of a sleeve 24 mounted on reduced portions 25 and 26 of the cones 18 105 and 21 respectively and said sleeve is secured to the first-mentioned cone by means of a screw 27.

It will be noted that the longitudinally movable sleeve 16 is provided with elongated slots 28 through which said pins 22 extend and the sleeve can, therefore, have a limited longitudinal movement with respect to the shaft 6 and pins 22.

An expansion member is further provided and said expansion member comprises a plurality of independent segments 29, 10 longitudinally extending and arranged together in a cylindrical formation. As shown in Fig. 4 the intermediate lower surfaces of said segments are rounded and normally engage the sleeve 16 while the lower faces of 15 each end portion of the segments are flattened and upwardly or outwardly inclined, as at 30. The flattened end faces of the segments engage the flattened and inclined faces of the cones 14 and 21 and are adapted to 20 ride upwardly thereon, being held by keys or ribs 31 which enter complementary keyways 32 in said segment faces. The segments 29 are normally held closely together and against the sleeve 16 by means of a pair 25 of annular coiled springs 33 positioned in annular recesses 34 in the outer surfaces of the segments.

In the operation of the improved expansion shaft, a core for a roll is slipped onto 30 the shaft so as to overlie the expansion member. Then, to clamp it firmly in position on the shaft, the adjusting member 10 is screwed so as to advance it toward the outer end of the shaft. This movement will cause the 35 tapered end of the cone 14 to wedge further under said segments and force the other ends of said segments upwardly on the faces 23 of the stationary cone 21, whereby said expansion member will be expanded against 40 the tension of the springs 33 and the circumference of the same enlarged, as shown in dotted lines in Fig. 1. Of course, the degree of expansion may be varied and when expanded the knurled faces of the segments 45 will firmly engage the roll or core and clamp it against slipping. The expansion member may be returned to normal position to release the core or roll.

It is obvious that a shaft may be equipped 50 with any number of the expansion devices and when that is the case the cone 18 in the drawing will provide the movable cone and spaced therefrom to the right will be another stationary cone and an expansion 55 member will be mounted between the tapered ends of said cones. When the adjusting member 10 is turned the cone 18 will be moved outwardly through contact with the

end portion of the sleeve 16 which is moved longitudinally on the shaft by the cone 14. 60

From the foregoing description it will be seen that the improved expansion shaft is of simple and novel construction, and is well adapted for the purpose set forth.

What I claim as my invention is: 65

1. An expansion shaft, comprising an elongated revoluble inner shaft of circular form in cross section and uniform diameter throughout its length, an expansion member mounted on an intermediate portion 70 thereof, said expansion member being formed of adjacent segments yieldingly held in juxtaposition and the end portions of each segment being wedge shaped, the sum of the lengths of the two wedge shaped end 75 portions of each segment being greater than the length of the intermediate portion, a stationary member formed with a tapered inner end portion engaging one set of said wedge shaped end portions of the segments, a member longitudinally movable on said shaft 80 and having a tapered end portion engaging the other set of said wedge shaped end portions of said segments, and a member revolvably mounted on the shaft for moving 85 said last-mentioned member.

2. An expansion shaft, comprising an elongated revoluble inner shaft, of circular form in cross section and uniform diameter throughout its length, an externally threaded 90 member mounted fast on said shaft, an elongated sleeve loosely mounted on an intermediate portion of said shaft, a stationary cone member mounted on the shaft and secured thereto, a longitudinally movable cone 95 member on said shaft, said cone members being spaced from each other and having downwardly tapered end portions directed toward each other, an adjusting member threadably mounted on said externally 100 threaded member and engaging said movable cone member, and an expansion member formed of a plurality of juxtaposed and yieldably connected segments, each segment having a pair of wedge shaped end 105 portions and each set of said end portions engage the tapered end portion of an adjacent cone member, the segments being uniformly separated by a relative movement of the cone members toward each other, the sum of the lengths of the two wedge shaped end portions of each segment being greater than the lengths of the intermediate portion.

In testimony whereof, I affix my signature.

JOSEPH F. STACHOWSKI.
